ATTORNEY

UNITED STATES PATENT OFFICE

CHARLES SAMUEL FRANKLIN, OF BUCKHURST HILL, ENGLAND, ASSIGNOR TO RADIO CORPORATION OF AMERICA, A CORPORATION OF DELAWARE

WIRELESS TELEGRAPH AND TELEPHONE AERIAL

Application filed July 31, 1925, Serial No. 47,232, and in Great Britain August 5, 1924. Renewed May 5, 1930.

This invention relates to wireless telegraph and telephone aerials and more particularly to wireless telegraph and telephone aerials which are long in proportion to the wave length used.

The object of my invention is to annul or suppress radiation from half wave length sections of an aerial.

Another object of my invention is to obtain greater efficiency in directional propagations of radio oscillations.

A further object of my invention is the employment of means by which alternate half waves are concentrated.

Other objects and advantages of my invention will appear as set forth more fully in the accompanying specification and by reference to the drawings, in which,

Fig. 1 shows the current distribution and polar diagram of a normal aerial one half wave length long.

Fig. 2 is a similar view showing the current distribution curve in three sections and polar diagram of a normal aerial one and a half wave lengths long as comprising six loops.

Fig. 3 is also a similar view wherein the aerial is shown as being substantially one and a half wave lengths long with the center portion of the aerial doubled back on itself and the resulting polar diagram.

In these figures, A represents the aerial, B the standing current distribution curve and C the polar diagram. In Fig. 2, it will be seen that the phases of the current as represented by the two end sections of the curve B are similar and in opposition to the phase of the current in the center section. In this figure, the polar diagram C consists of six loops, three on each side of the aerial A.

In Fig. 3, the aerial is shown as being looped back on itself so that the radiation from this loop portion is suppressed. The current distribution B in this aerial is simi-

lar to that shown in Fig. 2 but since radiation from the center portion is annulled, the radiation from the two end portions add in a direction at right angles to the aerial, giving a polar diagram approximately as shown at C whereby the aerial in consequence is shown to be much more directional than the aerial exhibited in Fig. 1.

It is known that if any aerial, half a wave length long, is excited electrostatically from one end, there is produced in the aerial a standing wave which has a maximum current value at the middle. Such an aerial radiates best at right angles to the direction of the wire, the polar curve in the plane of the wire being a figure of 8. If the aerial is one wave length long, then the standing wave has current maximum $\frac{1}{4}$ wave and $\frac{3}{4}$ wave along the wire. As the current in one half of the wire is opposite in phase to the current in the other half, such an aerial does not radiate in the direction at right angles to the wire, but radiates in two directions approximately 45° on each side of this right angle direction, the polar curve in the plane of the wire being four loops with zeros at right angles to the wire and in the direction of the wire. If the wire is one and a half wave lengths long, then the standing wave has three maxima of current at $\frac{1}{4}$, $\frac{3}{4}$ and $\frac{1}{2}$ wave lengths from the end, the phase of the currents at the $\frac{1}{4}$ and $\frac{3}{4}$ points being the same and opposite to that at the $\frac{1}{2}$ point, and the polar curve in the plane of the wire has six loops.

In general, if the length of the wire is n half wave lengths, then the polar curve in a plane of the wire will have $2n$ loops.

According to this invention, I annul or suppress radiation from every alternate half wave length, and so obtain a polar curve in a plane of the wire, having substantially only two loops which are in the direction at right angles to the wire, and the sharpness of which is dependent on the

length of the wire employed. I obtain this result by concentrating alternate half wave length portions of the wire within a small space, by winding such portions as inductance coils or by doubling such portions back on themselves so that there is practically no radiation from these portions.

The phases of the currents in the remaining portions are then all substantially the same and add their effects in the direction at right angles to the wire.

An aerial constructed in this manner may also be advantageously employed for receiving.

15 In a modification, in place of doubling back on themselves, those parts of the aerial from which it is desired to annul radiation, I may employ electrical equivalents, such as an inductance coil having sufficient natural capacity. The equivalent inserted to

20 replace the "doubling back" of the aerial should be substantially in tune with the frequency employed and should have small natural radiation compared with a straight 25 wire aerial of half wave length.

My invention may also be applied to a plurality of aerials arranged in a line and any desired degree of concentration may be obtained in planes passing through the center lines of the aerial system and parallel to the aerials.

Having thus described my invention, what I claim is new, and desire to secure by Letters Patent is:—

35 1. In a wireless system for transmission or reception; an antenna electrically long in comparison with the wave length employed and means integral with the antenna to suppress radiation from alternate half wave length portions of the antenna.

40 2. In a wireless system for transmission or reception; an antenna for obtaining directional effects comprising successive radiating and non-radiating portions of half wave length, each of said non-radiating portions being looped back on itself.

45 3. The method of obtaining directive transmission or reception by the use of an antenna long in comparison with the wave length employed, which consists in suppressing or annulling radiation from alternate half wave length portions of the antenna.

50 4. In a wireless system for transmission or reception, an antenna for obtaining directional effects comprising a plurality of radiating portions of substantially half wave length and a non-radiating portion of substantially half wave length interposed 55 between said radiating portions.

55 5. In an antenna system an aerial for obtaining directional communication including a pair of directional radiating portions and an intermediate non-radiating portion arranged to suppress radiation throughout

a portion of said aerial equal to an odd multiple of a half wave length for increasing directivity.

6. An antenna comprising a plurality of radiating and a plurality of substantially non-radiating reactances connected alternately in series, each having an electrical length of a half wave.

7. An antenna comprising a plurality of half wave length radiating wires located end to end, and phase changing means connecting said wires in series with a change in phase sufficient to make the radiation from said wires cophasal.

8. An antenna comprising a plurality of radiating wires, each a half wave in electrical length, located end to end, and inductance a half wave in electrical length for connecting two of said radiating wires in series.

9. An antenna comprising a long wire and a plurality of poorly radiating reactors each a half wave in electrical length inserted in series with the wires and spaced an electrical half wave apart along the wire.

10. In a radiating system for radiating high frequency energy, a pair of radiators and a non-radiating element effectively one-half wave length long between the radiators for establishing electrical connection between the radiators.

11. In a radiating system for radiating high frequency energy, a pair of radiators and a looped non-radiating element one-half wave length long between the radiators for establishing electrical connection between the radiators.

12. In a radiating system for radiating high frequency energy, a pair of radiators and means connecting the radiators together at adjacent ends thereof, comprising a linear wire one-half wave length long looped upon itself so as to be non-radiating.

13. In a system utilizing high frequency currents, a substantially straight conductor carrying high frequency currents, another substantially straight conductor carrying high frequency currents adjacent the first mentioned conductor, and a non-radiating element consisting of a U-shaped conductor substantially one-half wave length long connecting adjacent ends of the conductors.

14. In a system utilizing high frequency currents, a part carrying high frequency currents, another part carrying high frequency currents, and a connection for connecting adjacent terminals of the parts consisting of a wire looped upon itself so that it is in the form of a U with legs relatively close together whereby the element acts as a non-radiating phase changer.

15. A connecting element, for use in a system utilizing radio frequency currents for connecting two parts of the system together.

and for producing a phase change in currents flowing from one part to the other of substantially 180 degrees, consisting of a wire substantially one-half wave length long 5 looped upon itself so that it is in the shape of a **U** having legs relatively close together.

16. In a system utilizing high frequency currents, a part carrying high frequency currents, another part carrying high frequency currents, and a connection for connecting adjacent points of the parts consisting of an arrangement in the form of a **U** having conducting legs relatively close together whereby the arrangement acts as 15 a non-radiating phase changer.

17. A connecting element, for use in a system utilizing high frequency currents, for connecting two parts of the system together and for producing a phase change in currents flowing from one part to the other of substantially 180 degrees, consisting of a **U**-shaped arrangement having conducting legs close together whereby radiation from the 20 legs is effectively prevented.

25. 18. In a system utilizing high frequency currents, a substantially straight conductor carrying high frequency currents, another substantially straight conductor carrying high frequency currents adjacent the first 30 mentioned conductor, and, a non-radiating high frequency connecting arrangement for connecting adjacent points on said adjacent conductors, said arrangement being in the form of a **U** and having conducting legs 35 relatively close together whereby radiation from the arrangement is substantially negligible.

19. In a system for transmitting undulatory high frequency electrical energy, a pair 40 of substantially straight wires, and means connecting adjacent points on the wires consisting of a conductive arrangement in the form of a **U** having legs close together whereby radiation from said arrangement is 45 substantially negligible.

20. An antenna system for radiating or receiving electromagnetic waves comprising separated linear radiators, each a half wave length long, and arranged coaxially on a 50 straight line, and, a rectangular **U**-shaped conductor connecting adjacent ends of said radiators.

21. An antenna system comprising a pair of straight wires separated and arranged 55 coaxially, and, a rectangular **U**-shaped conductor joining adjacent ends of said separated wires.

22. An antenna system comprising a straight wire, a conductor connected to one 60 end of said wire and at right angles thereto, another conductor perpendicular to and connected to the free end of said first mentioned conductor, another wire coaxial with but separated from said first mentioned 65 wire, and a conductor, perpendicular and

joining both said last mentioned conductor and one end of said last mentioned wire.

23. An antenna system comprising two straight wires each a half wave length long and arranged coaxially but separated from each other, and, a **U**-shaped conducting element formed of substantially straight wires, the free ends of the legs of said **U**-shaped conductor joining adjacent ends of said separated wires. 70
